ADOLPH BECKER, OF WHEELING, WEST VIRGINIA.

MATRIX AND DISTRIBUTING APPARATUS FOR TYPE-CASTING MACHINES.

1,422,333.

Specification of Letters Patent. Patented July 11, 1922.

Application filed April 23, 1921. Serial No. 463,867.

To all whom it may concern:

Be it known that I, ADOLPH BECKER, a citizen of the United States, and resident of Wheeling, in the county of Ohio and State 5 of West Virginia, have invented a new and useful Improvement in Matrices and Distributing Apparatus for Type-Casting Machines; and I do hereby declare the following to be a full, clear, and exact description 10 thereof.

My invention relates to type-casting machines of the kind in which character matrices are assembled for molding each type bar and are thereafter elevated and distributed to the matrix magazines.

The general object of my invention is to elevate the matrices and deliver them to the distributor bar without making use of the combination teeth which control the delivery 20 of the matrices to the magazine channels, thus preventing the teeth from becoming damaged.

Another object of my invention is to provide an improved matrix construction 25 whereby the matrix is held during elevating and delivery to the distributor bar by means other than the distributing teeth.

A further object of my invention is to provide an improved construction for the second 30 elevator bar and the distributor box bar, whereby these parts cooperate properly with my improved matrices.

In the accompanying drawing, Fig. 1 is a perspective view of a second-elevator head 35 having a matrix-carrying bar constructed in accordance with my invention, and showing a set of matrices suspended from the bar; Fig. 2 is a front elevational view of the elevator head shown in Fig. 1 when the elevator 40 is in its upper position, this figure also showing the distributor box bar and the end of the distributor bar; Fig. 3 is a side elevation, partly in section along the line 3—3, Fig. 2, showing the manner in which the 45 matrices are held on the elevator bar; Fig. 4 is an end elevational view of the distributor box bar, this construction being common to the elevator bar, the distributor box bar, and the front end of the distributor bar; Fig. 5 is a side elevation of a matrix 50 constructed in accordance with my invention; and Fig. 6 is a side elevational view of the upper end of a spaceband adapted for use with my improved matrices.

In linotype machines and other type-casting machines of the same general nature, the

elevator bar and the distributor box bar are both provided on their converging under sides with grooves which support the matrices by engaging the teeth formed on the 60 V-shaped notch in the top of each matrix, these same teeth being employed for distributing the matrices into the magazine channels and being for this purpose arranged in definite combinations. In the operation of 65 the machine the grooves on the elevator bar become worn and burred by striking against the spacebands when the second elevator lowers to pick up the matrices, and the grooves on the elevator bar and the distributor box bar may also be slightly out of 70 alignment at the time when the matrices are pushed from the elevator bar upon the distributor box bar. Any such distortion or unevenness in the grooves catches the teeth 75 of the matrices as they are pushed along the grooves, and thus quickly wears out some of the teeth, with the result that the matrices will not distribute properly, but fall off the distributor bar either too soon or too late, 80 and so are distributed into the wrong channels, or may even jam the machine. The expense of replacing worn matrices is probably the largest single item of expense in machines of this kind.

According to my present invention, the combination teeth on the matrices are not used for handling the matrices at any time while the matrices are being raised by the second elevator, pushed through the distributor box, or lifted upon the distributor, and therefore the life of the matrices is extended indefinitely. I accomplish this result by providing at the bottom of the V-notch of each matrix an opening having a 90 restricted connection with the V-notch, and by providing the elevator bar and the distributor box bar with beaded supporting strips shaped to conform to the openings in the matrices. The end of the distributor 100 bar itself is also preferably provided with a short section similar to the distributor box bar. The matrices are thus suspended from the lugs formed by the upper portions of these openings at all times while the matrices are being elevated and transferred to the distributor bar. When the matrices are upon the distributor bar the advancing screws carry them on to the ordinary distributing grooves and the combination teeth 105 here come into play for the first time. These teeth are in contact with the distributor bar 110

for a few moments only, so that the wear of the teeth is reduced to a minimum. Other advantages of my invention having to do with the collection of special-character matrices and the proper lifting of the matrices from the distributor box to the distributor bar will appear as the description proceeds.

In the accompanying drawing the numeral 2 designates the second-elevator head 10 of an ordinary linotype machine. This elevator head may be of any usual or desired construction, except for the bar 3 from which the matrices 4 are suspended. This bar, as best shown in Figs. 3 and 4, has downwardly 15 converging smooth undersides 5, below which is a thin strip 6 having an enlarged bead 7 formed on its lower edge. The strip 6 may be formed integral with the bar 3, or may, as shown, be inserted in a slot formed in the 20 lower edge of the bar.

As shown in Figs. 3 and 5, each matrix 4 is of ordinary construction, except that it has an opening 10 communicating with the toothed V-notch 11 by means of a restricted 25 channel 12. The opening 10 and the channel 12 are of such size and shape that they fit the bead 7 and the strip 6 in the manner shown in Fig. 3. The converging sides 5 of the bar 3 are formed at such an angle that a 30 clearance space 13 is provided between the teeth 14 and the sides 5 of the bar. It will thus be seen that when the matrices are slid upon the bar 3 they are held suspended by the engagement of the bead 7 in the openings 35 10 of the matrices. As shown, the bead 7 and the opening 10 are circular, and while this is the preferable form, these parts may of course be made in any other desired shape, so long as they fit properly together.

40 Fig. 2 shows the elevator head 2 in its upper position in which it registers with the distributor box bar 20, the other parts of the distributor box being omitted for the sake of clearness. The distributor box bar 20 is 45 of the same cross-sectional form as the elevator bar 3 and has a bead 7^a along its lower edge corresponding to the bead 7 on the elevator bar 3. It will thus be evident that when the matrices 3 are raised by the elevator into the position shown on Fig. 2 and are then pushed to the right by the usual pusher, they will slide upon the bar 20, as shown at 4^b, each matrix being still carried upon the bead 7^a and the combination teeth 55 14 being still untouched. Even if there should be a slight unevenness at the joint between the elevator bar and the distributor box bar, the only damage to the matrices that can result will be a slight flattening at 60 the edges of the openings 10, which will do no great harm.

At the right of Fig. 2 is shown the end of the distributor bar 21, having the usual grooves 22 terminating, as usual, some distance short of the front end of the distribu-

tor bar. I prefer that this ungrooved front end of the distributor bar 21 be provided with a bead 7^b similar in cross section to the beads 7 and 7^a on the elevator bar and on the distributor box bar. The purpose of this 70 bead 7^b is to support the matrices after they are lifted by the usual lifting finger, not shown, from the distributor box bar to the distributor bar, so that each matrix is started properly upon the distributor bar before the 75 combination teeth 14 come into contact with the distributing grooves 22.

Fig. 6 shows a spaceband 25 adapted for use with the matrices of my invention. This spaceband is of ordinary construction, except 80 that it has a central notch 27 at least as large as the openings 10 in the matrices, so that the matrices may be lifted away from the spacebands by the second elevator without interfering in any way with the spacebands 85 6.

In the operation of the machine, the matrices and spacebands are assembled in the usual manner, and after the type bar is cast the matrices and spacebands are raised by 90 the first elevator and are slid upon the second elevator bar 3, the matrices being supported entirely by the bead 7, as shown in Fig. 3. The second elevator then rises, lifting the matrices away from the spacebands 95 and bringing them into the position shown in Fig. 2 whereupon the pusher transfers the matrices from the elevator bar 3 to the elevator box bar 20 and thence into position to be raised by the lifter, not shown, to the 100 level of the distributor bar 21, where the usual advancing screws, which are also omitted from the drawing for the sake of clearness, take hold of each matrix and carry it along the distributor bar 21. In the first 105 portion of its travel along the distributor bar, the matrix is still supported by its center opening 10 which travels on the short bead 7^b, and by the time that the combination teeth 14 reach the grooves 22 the matrix is in proper position and the teeth pass smoothly into the grooves. Thereafter the matrices drop from the distributor into the magazine channels as usual.

110 My invention has numerous advantages, among which are the saving of trouble and expense in renewing matrices, and also in renewing elevator bars and distributor box bars. The elevator bars, in particular, become quickly worn out in ordinary machines 115 and must constantly be replaced.

120 My invention increases production by saving numerous distributor stops and will eliminate to a certain extent the dropping of matrices into the wrong channel, thereby 125 saving the resetting of many type bars having typographical errors due to improper distribution of matrices.

In addition to these advantages, my invention makes it possible to handle space 130

matrices, special-character matrices, and damaged matrices more conveniently than can be done with ordinary machines. The space matrices, instead of dropping into a 5 pi-box when the character matrices are elevated, may be provided with openings 10 similar to those in the matrices and will then be elevated along with the character matrices and may be distributed into the 10 first channel in the magazine, which channel is ordinarily left vacant. The space matrices have no combination teeth and will drop off the distributor bar as soon as they reach the end of the short bead 7^b on the 15 bar 21. In the same way, damaged matrices may also be received in the first channel. Extra characters may also be recovered in the first channel instead of being carried to the end of the machine, in which case one 20 or more pi-stacker boxes may be arranged at the bottom of the first channel of the magazine, the channel being provided with a universal gate for directing the space matrices and special-character matrices into 25 the proper stacker boxes.

Another modification made possible by my invention consists in adding to the right end of the ordinary distributor bar a section having the form shown in Fig. 4, so 30 that sorts and matrices having special characters may be caused to travel the full length of the distributor bar, as is now customary, and instead of falling into the usual sorts-stacker channel may be carried 35 on upon the beaded extension for any suitable distance and may then be distributed into stacker boxes arranged conveniently below this point. Some amount of distribution can here be produced by modifying 40 the shape of the openings 10 in the sorts and special-character matrices, so that after passing the full length of the distributor bar these matrices may be distributed into separate channels or separate pi-boxes.

45 It will also be observed that my improved elevator bar and distributor box bar may be applied to any ordinary type-casting machine without any change, except in the matrices used. Also, my improved elevator 50 bar may be used in conjunction with an old-style distributor box bar, or my improved distributor box bar may be used with an old-style elevator bar, although the best results are produced by having both the elevator 55 bar and the distributor bar constructed in the manner here shown. When my improved elevator bar is used with an old-style distributor box bar it is only necessary to smooth off the end of the distributor box 60 bar so as to fit the elevator bar.

In the claims the expression "transfer member" is intended to include a second elevator bar, a distributor box bar, or a distributor bar.

65 While I have shown and described herein

the form in which I prefer at present to employ my invention, it will be understood that various changes can be made without departing from the principles of my invention, the scope of which is indicated in the 70 appended claims.

I claim as my invention:

1. In a type-casting machine, the combination with a set of matrices each having a V-shaped notch, and having an opening 75 adjacent to the said notch and communicating therewith by a restricted channel, of a transfer member having a beaded strip adapted to enter the said openings and to suspend the said matrices during transfer 80 without engaging the sides of said V-notches.

2. In a type-casting machine, the combination with a set of character matrices, each having a V-shaped notch and having combination teeth formed on the sides of said notch and also having an opening adjacent to the angle of said notch and communicating therewith by a restricted channel, of a transfer member having a beaded strip adapted to 85 enter said openings and to suspend the said matrices during transfer without engaging the said combination teeth.

3. In a type-casting machine, the combination with a set of matrices each having a 95 V-shaped notch, and having a circular opening adjacent to the angle of the said notch and communicating therewith by a restricted channel of a transfer member having a matrix-suspending strip provided with a 100 bead adapted to enter the said openings in the said matrices, the said transfer member being adapted to enter said V notches without engaging the sides thereof.

4. A matrix for type-casting machines having a V-shaped notch and a circular opening 105 adjacent to the angle of the said notch and communicating therewith through a restricted channel.

5. A transfer bar for handling V-notched 110 matrices in type-casting machines comprising a bar having sides, converging downwardly at an angle less than the angle of the V-notches in said matrices, a strip extending lengthwise of the said bar at the angle between the said converging sides, and a matrix-suspending bead on the outer edge of the said strip.

6. A transfer bar for handling V-notched 115 matrices in type-casting machines, having sides, converging downwardly at an angle less than the angle of the V-notches in said matrices, a strip of thin sheet metal extending lengthwise of the said bar at the angle between the said converging sides, and a 120 matrix-supporting bead of substantially circular section formed on the outer edge of the said strip.

7. In a type-casting machine, the combination of a set of matrices, each having a V- 125

- shaped notch and a suspending opening adjacent to the said notch, an elevator bar and a distributor box bar adapted to register with the said elevator bar when the said elevator bar is in its upper position, the said elevator bar and distributor box bar being provided with means for passing through the said openings in the said matrices and for thereby suspending the said matrices independently of their combination teeth.
8. In a type-casting machine, the combination of a set of matrices, each having a V-shaped notch and a suspending opening communicating with the said notch, an elevator bar and a distributor box bar adapted to register with the said elevator bar when the said elevator bar is in its upper position, the said elevator bar and distributor box bar being provided with downwardly extending strips having matrix-supporting beads adapted to enter said openings in said matrices and to thereby support said matrices independently of their combination teeth.
9. In a type-casting machine, the combination of a set of matrices, each having a V-shaped notch and a suspending opening adjacent to said notch and communicating therewith through a restricted channel, a second-elevator head provided with a matrix-supporting bar having downwardly converging sides, a strip extending lengthwise of the said bar and provided with a matrix-supporting bead adapted to enter the openings in the said matrices, a distributor box bar registering with the said elevator bar when the said elevator is in its upper position, the said distributor box bar being of substantially the same construction as the said elevator bar, and a distributor bar having one end adjacent to the said distributor box bar, the said end of the said distributor bar having a short section formed to support the said matrices by the said openings while the said matrices are beginning their advance along the said distributor bar.
10. In a type-casting machine, the combination of a set of matrices, each having a V-shaped notch and a suspending opening adjacent to said notch and communicating therewith through a restricted channel, a second-elevator head provided with a matrix-supporting bar having downwardly converging sides, a strip extending lengthwise of the said bar and provided with a matrix-supporting bead adapted to enter the said openings in the said matrices, a distributor box bar registering with the said elevator bar when the said elevator is in its upper position, the said distributor box bar being of substantially the same construction as the said elevator bar, and a distributor bar having both of its ends provided with matrix-supporting beads similar to those on the said elevator bar and the said distributor box bar, and having the usual distributing grooves on the remainder of its length.

In testimony whereof, I the said ADOLPH BECKER have hereunto set my hand.

ADOLPH BECKER.
